ELECTRICAL CONNECTOR

Oscar F. Tallman, St. Louis, Mo., assignor to
 James R. Kearney Corporation, St. Louis, Mo.,
 a corporation of Missouri

Application May 10, 1937, Serial No. 141,599

6 Claims. (Cl. 24—125)

This invention relates generally to electrical connectors and more specifically to wire connectors of the split bolt type which are used extensively in the construction, repair, and maintenance of electric wire systems for connecting tap or service lines or ground wires to main lines, and for numerous other purposes, such, for instance, as connecting wires to articles of electrical equipment, the predominant object of the invention being to provide a connector of the type mentioned which is of such improved construction and arrangement that the function of the connector is performed in an improved and highly efficient manner.

15 Connectors of the type to which this invention relates comprise a bolt in which a slot is formed longitudinally thereof, said slot being open at one end of the bolt and terminating at its opposite end in a wire seat which receives a wire to be clamped. The opposed legs of the slotted bolt are exteriorly screwthreaded throughout most of their lengths and screwthreadedly mounted on the screwthreaded portions of the legs of the bolt is a nut which has associated therewith a washer, said washer being movable longitudinally 20 of the bolt of the connector with the nut but being restrained from rotary movement with said nut by a portion of the washer which extends into the slot of the bolt. The washer ordinarily is provided with a wire seat which is movable into and out of wire clamping relation with respect to the wire seat of the bolt by manipulation of the nut.

A source of considerable annoyance in the use 35 of connectors of the type described is that it is not always possible to obtain connectors having screwthreads on the bolts and within the nuts thereof which are formed with such precision as to provide the desired intimate contact and perfect cooperation between the screw- 40 threads of the nuts and bolts. The main purpose of this invention, therefore, is to provide an improved connector having a washer of such unique construction and arrangement that when 45 pressure is applied to elements being clamped between the seats of the bolt and the washer, such pressure will spread opposed portions of the washer in such manner as to force the legs of the bolt outwardly away from each other. This 50 results in the screwthreads on the legs of the bolt being forced into intimate contact with the screwthreads of the nut to provide the desired close cooperation between the screwthreads of the bolt and the nut of the connector.

55 Another object of the invention is to provide

a connector of the type to which this invention relates which is provided with a washer formed by bending into proper shape one or more elongated strips of material such as relatively heavy wire or the like. By providing the improved connector with a washer of the type mentioned the connector and the manufacture thereof are simplified without in any manner impairing the efficiency of the connector.

Fig. 1 is a side elevation of the improved connector.

Fig. 2 is a vertical section through the connector illustrated in Fig. 1.

Fig. 3 is a section taken on line 3—3 of Fig. 1.

Fig. 4 is a horizontal section taken on line 4—4 of Fig. 1.

Fig. 5 is a perspective of a modified form of the washer of the improved connector.

In the drawing, wherein are shown for purposes of illustration, merely, two embodiments of the invention, A designates, in Figs. 1, 2, 3, and 4, the improved connector generally. The connector A includes a bolt 1 which is provided at one of its ends with a head 2 preferably, though not necessarily, of noncircular shape so that a tool 20 may be applied thereto if desired. The bolt 1 has formed longitudinally thereof a slot 3 which is open at an end of the bolt and at its opposite end terminates in a wire seat 4 which is located at the lower portion of the head 2. The presence of 30 the slot 3 in the bolt 1 of the connector provides said bolt with opposed legs 1' which throughout at least a portion of their lengths are externally screwthreaded as indicated at 5.

Mounted on the screwthreaded portions of the 35 bolt 1 is a nut 6 and associated with said nut in assembled relation therewith is a washer 7. The washer 7 shown in Figs. 1, 2, 3, and 4 is in the form of two, independent washer portions 7a and 7b and each washer portion includes an arcuate 40 portion 8 which is arranged in embracing relation with respect to the curved outer face of the adjacent leg 1' of the bolt as shown to the best advantage in Fig. 4. The lower faces of the arcuate portions 8 of the washer portions 7a and 7b contact with the top face 6' of the nut as these parts are positioned in Figs. 1 to 4 inclusive, and each washer portion 7a and 7b includes portions 9 which extend inwardly toward each other from the opposite ends of the arcuate portion 8 of said 50 washer portion as shown in Fig. 4. From the inner ends of the inwardly extended portions 9 of each washer portion 7a and 7b portions 10 of the washer portion extend downwardly through the bore of the nut 6, and the lower portions 11 55

of such downwardly extended portions are bent outwardly so as to underlie the lower face of the nut as shown to the best advantage in Fig. 3. At opposite sides of the washer 7 the adjacent, inwardly extended portions 9, downwardly extended portions 10, and outwardly bent portions 11 of the associated washer portions 1a and 1b are disposed adjacent to each other, and when the nut and washer assembly is mounted on the bolt these adjacently disposed portions of said associated washer portions are located in the slot of the bolt as shown in Fig. 3 where they substantially fill the opposite end portions of the bolt slot in a transverse direction.

15 When the washer is being assembled with the nut, the outwardly bent portions 11 of the washer portions 1a and 1b extend downwardly in continuation of the portions 10 of said washer portions and the portions 10-11 of both washer portions are passed through the bore of the nut so as to seat the inner faces of the arcuate portions 8 of the washer portions on the face 6' of the nut. The portions 11 of the washer portions are then bent outwardly, as shown in Fig. 3, so that they underlie the opposite face of the nut. It is obvious that when the washer and nut have been assembled as described the washer portions may not be displaced to any great extent from their proper effective positions. This is so because the opposed portions 10 and 11 of each washer portion, being located in close proximity to opposed portions of the screwthreaded wall of the bore of the nut, prevent any great amount of movement transversely of the nut. Also very little movement of the washer portions away from each other is permitted because the portions 10-11 of said washer portions will contact with the screwthreaded wall of the bore of the nut to prevent such movement. It is to be noted that Figs. 1, 2, 3, and 4 of the drawing are considerably enlarged over the actual sizes of the connectors with a consequent increase in spaces and clearances. In the actual devices much less opportunity for movement of the washer portions with respect to the nut is present than appears in the greatly enlarged views of the drawing.

50 The adjacently disposed, inwardly extended, portions 9 of the associated washer portions 1a and 1b which are located at opposite sides of the washer are provided with inclined faces 12 and the inclined faces of each associated pair of portions 9 provide a seat for a wire or other element being clamped by the connector. As shown in Fig. 3 the seats at opposite sides of the washer are aligned with each other transversely of the slot of the bolt when the nut and washer assembly are mounted on the bolt.

55 In the use of the improved connector illustrated in the drawing, the nut and washer assembly may be removed from the bolt to permit said bolt to be passed over a wire L which may be considered a power line. The nut and washer assembly is then screwed on the screwthreaded portions of the bolt with the arcuate portions 8 of the washer portions 1a and 1b embracing the outer curved faces of the legs of the bolt, and with the portions 10-11 of said washer portions disposed within the slot of the bolt. The wire G which is to be electrically connected to the wire L, a ground wire, for instance, is then arranged in place and the nut and washer assembly is screwed longitudinally of the bolt until the wires L and G are tightly clamped between the seats 4 and 12 of the bolt and washer, during such movement the nut

being rotated with respect to the washer which moves in a straight line.

An extremely important feature of the invention is that when pressure is applied to the wires L and G to force them tightly together so that perfect electrical connection between said wires is provided, such pressure forces the curved surface of the wire G and the inclined seat faces 12 of the washer portions 1a and 1b into such close contact with each other that a camming action 10 takes place which forces the washer portions outwardly from each other. This outward movement of the washer portions is transmitted to the legs 1' of the bolt by the washer portions located between said legs of the bolt with the result that 15 said bolt legs are sprung outwardly slightly. As a result of the bolt legs being sprung outwardly as described the screwthreads formed on said bolt legs are forced into close cooperating relation with respect to the screwthreads within the bore 20 of the nut whereby the desirable play-free co-operation between the screwthreads of the nut and bolt is obtained.

In Fig. 5 is illustrated a washer 13 which is made from a single length of material. In accordance 25 with this form of the invention the washer portions 13a and 13b, which correspond to the washer portions 1a and 1b illustrated in Figs. 1 to 4, inclusive, are formed of the same length of material and are joined together as indicated at 14. 30 In the use of this form of washer, the washer portions are spread apart just as are the separate washer portions shown in Figs. 1 to 4, inclusive, to provide close cooperation between the screw- 35 threads of the bolt legs and the nut, as the material of which the one-piece washer of Fig. 5 is formed is possessed of sufficient spring to permit such movement.

While I have shown in the drawing two forms of washers which are made from material of 40 rectangular cross-section, it is to be understood that the washers may be made from material of round or other cross-sectional shapes without departing from the spirit of the invention.

I claim:

1. An electrical connector comprising a bolt having spaced, exteriorly screwthreaded legs, a nut mounted on said screwthreaded bolt legs, and a washer arranged in assembled relation with respect to said nut and having portions which extend into the space between the legs of the bolt, said washer including independent, substantially parallel portions movable outwardly away from each other when pressure is applied thereagainst and said outward movement of said washer portions being transmitted to the legs of the bolt by the washer portions between said bolt legs whereby the screwthreads of the bolt legs are forced into close cooperating relation with respect to the screwthreads of the nut. 50

2. An electrical connector comprising a bolt having spaced, exteriorly screwthreaded legs, a nut mounted on said screwthreaded bolt legs, a washer arranged in assembled relation with respect to said nut and having portions which extend into the space between the legs of the bolt, and cam faces formed on portions of said washer, said washer including opposed portions movable outwardly away from each other when pressure is directed against said cam faces as a result of 65 clamping pressure being applied to an element by said washer, and said outward movement of said washer portions being transmitted to the legs of the bolt by the washer portions between the legs of the bolt whereby the screwthreads of the 70 75

bolt legs are forced into close cooperating relation with respect to the screwthreads of the nut.

3. An electrical connector comprising a bolt having spaced, exteriorly screwthreaded legs, a nut mounted on said screwthreaded bolt legs, a washer arranged in assembled relation with respect to said nut and having portions which extend into the space between the legs of the bolt, and cam faces formed on portions of said washer which provide wire seats, said washer including opposed portions movable outwardly away from each other when pressure is directed against said cam faces as a result of clamping pressure being applied to an element by said washer, and said outward movement of said washer portions being transmitted to the legs of the bolt by the washer portions between the legs of the bolt whereby the screwthreads of the bolt legs are forced into close cooperating relation with respect to the screwthreads of the nut.

4. An electrical connector comprising a bolt having spaced, exteriorly screwthreaded legs, a nut mounted on said screwthreaded bolt legs, a washer arranged in assembled relation with respect to said nut and having portions which extend into the space between the legs of the bolt, and inclined cam faces formed on portions of said washer, said washer including opposed portions movable outwardly away from each other when pressure is directed against said cam faces as a result of clamping pressure being applied to an element by said washer, and said outward movement of said washer portions being transmitted to the legs of the bolt by the washer portions between the legs of the bolt whereby the screwthreads of the bolt legs are forced into close cooperating relation with respect to the screwthreads of the nut.

5. An electrical connector comprising a bolt having spaced, exteriorly screwthreaded legs, a nut mounted on said screwthreaded bolt legs, and a washer arranged in assembled relation with respect to said nut, said washer being formed of elongated material in strand form bent and shaped to provide portions which contact with a face of the nut and portions which extend through the bore of the nut and underlie an opposite face of the nut, said washer portions which extend through the bore of the nut being located in the space between the legs of the bolt, independent, substantially parallel portions of said washer being movable outwardly away from each other when pressure is directed thereagainst as a result of clamping pressure applied to an element by said washer, and such outward movement of said washer portions being transmitted to the legs of the bolt whereby the screwthreads of the bolt legs are forced into close cooperating relation with respect to the screwthreads of the nut.

shaped to provide portions which contact with a face of the nut and portions which extend through the bore of the nut and underlie an opposite face of the nut, said washer portions which extend through the bore of the nut being located in the space between the legs of the bolt, independent, substantially parallel portions of said washer being movable outwardly away from each other when pressure is directed thereagainst as a result of clamping pressure applied to an element by said washer, and such outward movement of said washer portions being transmitted to the legs of the bolt whereby the screwthreads of the bolt legs are forced into close cooperating relation with respect to the screwthreads of the nut.

6. An electrical connector comprising a bolt having spaced, exteriorly screwthreaded legs, a nut mounted on said screwthreaded bolt legs, a washer arranged in assembled relation with respect to said nut, said washer being formed of elongated material in strand form bent and shaped to provide portions which contact with a face of the nut and portions which extend through the bore of the nut and underlie an opposite face of the nut, said washer portions which extend through the bore of the nut being located in the space between the legs of the bolt, opposed portions of said washer being movable outwardly away from each other when pressure is directed thereagainst as a result of clamping pressure applied to an element by said washer, and such outward movement of said washer portions being transmitted to the legs of the bolt by the washer portions between said legs of the bolt whereby the screwthreads of the bolt legs are forced into close cooperating relation with respect to the screwthreads of the nut, and cam faces formed on portions of said washer, said cam faces providing wire seats and receiving thereagainst the pressure which moves said opposed washer portions outwardly.

OSCAR F. TALLMAN.
